UNITED STATES PATENT OFFICE.

ALLAN KIRKWOOD MACDONALD, OF HAMILTON, ONTARIO, CANADA.

RAILROAD-CROSSING-GATE LAMP.

Specification of Letters Patent.

Patented Nov. 16, 1915.

1,160,303.

Application filed June 5, 1915. Serial No. 32,469.

To all whom it may concern:

Be it known that I, ALLAN KIRKWOOD MACDONALD, a subject of the King of Great Britain, residing at Hamilton, in the county of Wentworth and Province of Ontario, Canada, have invented a new and useful Railroad-Crossing-Gate Lamp, of which the following is a specification.

My invention relates to improvements in railroad crossing gate lamps, and consists of a two-way shield or blind, adjustable to an ordinary railroad lamp; and the objects of my improvement are, first, to provide means by which a common red, or danger signal railroad lamp can be used to advantage for a gate lamp, second, to provide means that will permit the red light to be seen only by pedestrians, or vehicular traffic which may be approaching the railroad crossing, and at the same time rendering the light invisible to engineers or trainmen approaching the highway crossing on the railway, thereby not confusing them, third, to afford means for increasing the power or brilliancy of the red light, that it may be more efficient in warning the general public of the impending danger.

I attain these objects by the device illustrated in the accompanying drawing, in which,—

Figure 1 is a side elevation of the device, shown attached to the lamp; Fig. 2 a front elevation of the same; Fig. 3 a top view of the device in disconnection with the lamp.

Similar characters of reference refer to similar parts throughout the several views.

The device consists of two similar semi-circular sections or parts A and B, forming a casing, having light outlets 3, and provided with light concentrators or reflectors 4.

Copies of this patent may be obtained for five cents each, by addressing the "Commissioner of Patents, Washington, D. C."

The said parts are hinged together at C, and are fastened at 2 by a lock pin D, thereby forming a cylinder with open ends for facilitating the adjustment of the device to the lamp 6.

The device is suspended to the top casting 5 of the lamp 6 by means of the lugs E, which extend over the said top. The lugs E are also adapted to engage with the lamp handle 7, thereby preventing any chance turning, or misplacing of the device.

It can be readily observed that the device can be attached to any common railroad lamp without any special adjustment. Also it may be seen that by the use of the device the light is made more intense by means of the polished inside acting as a reflector, and by the concentrators 4.

The open ended, cylindrical blind is applicable to lamps of the class described, either in halves as set forth, or may be set on over the lamp in one piece.

I claim:

1. In a railway crossing gate lamp having a two way cylindrical casing constituting a blind having both ends open, and two opposite openings in the sides thereof, light reflectors around said openings, and lugs on the upper part of the casing to suspend the casing from the dome of the lamp.

2. In a railroad crossing gate lamp having a two way cylindrical casing constituting a blind having both ends open, and two opposite openings in the sides thereof, and light reflectors around said openings.

ALLAN KIRKWOOD MACDONALD.
